(57) CLAIM

The ornamental design for a shoe, as shown and described.

DESCRIPTION

FIG. 1 is a bottom view of a shoe showing my new design;
FIG. 2 is a side view thereof;
FIG. 3 is an opposite side view thereof;
FIG. 4 is a front perspective view thereof;
FIG. 5 is an opposite front perspective view thereof;
FIG. 6 is a rear perspective view thereof; and,
FIG. 7 is an opposite rear perspective view thereof.
The broken lines immediately adjacent to the shaded area define the bounds of the claimed design and form no part thereof. The broken lines depicting the remainder of the shoe show features that form no part of the claimed design.

1 Claim, 7 Drawing Sheets---
